(57) **CLAIM**

The ornamental design for a storage bag as shown and described.

DESCRIPTION

FIG. 1 is a perspective view of a storage bag showing a first embodiment of my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a storage bag showing a third second embodiment of my new design;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view thereof in the opened state;

FIG. 16 is a front view thereof in the opened state;

FIG. 17 is a rear view thereof in the opened state;

FIG. 18 is a left side view thereof in the opened state;

FIG. 19 is a right side view thereof in the opened state;

FIG. 20 is a top view thereof in the opened state;

FIG. 21 is a bottom view thereof in the opened state;

FIG. 22 is a cross-sectional view taken along line 22-22 in FIG. 16;

FIG. 23 is a top view thereof in the opened state with the inner lid opened; and

FIG. 24 is a perspective view thereof in the opened state with the head mounted display placed.

The dashed broken lines illustrate portions of the article that form no part of the claimed design. The dashed broken lines showing a head mounted display in FIG. 24 are for the purpose of illustrating environmental structure, and form no part of the claimed design.

1 Claim, 24 Drawing Sheets
